UNITED STATES PATENT OFFICE.

JAMES S. KNOWLSON, OF OAK PARK, ILLINOIS, ASSIGNOR TO ELECTRO-MAGNETIC TOOL COMPANY, OF CHICAGO, ILLINOIS, A CORPORATION OF ILLINOIS.

ELECTRICALLY-OPERATED TOOL.

1,298,966.

Specification of Letters Patent. Patented Apr. 1, 1919.

Application filed June 16, 1915. Serial No. 34,523.

To all whom it may concern:

Be it known that I, JAMES S. KNOWLSON, a citizen of the United States, residing at Oak Park, in the county of Cook and State 5 of Illinois, have invented certain new and useful Improvements in Electrically-Operated Tools, of which the following is a specification.

My invention relates to an electrically operated percussion tool, for riveting, drilling, 10 chipping, or other like purposes, of the general type shown in the patent to George H. Rowe, No. 938,709, patented November 2, 1909; and one of the principal objects of the 15 invention is to provide a tool of this character which may be operated from an alternating current circuit or, preferably, by either an alternating current or a direct current whichever is available. A tool of this type 20 consists, generally speaking, of an electromagnet having an armature, constituting the driven element of the tool, and means for shifting the field flux of the magnet by either moving the magnet itself or by im- 25 parting movement—for example, reciprocating movement,—to a sleeve of magnetizable metal, the ends of which sleeve are substantially insulated from each other and which is interposed between the coil of the magnet 30 and its armature core. By this means move- 35 ment is imparted to the driven or percussion element and the impacts thereof against the tool shank are cushioned. If the percussion element is reciprocated, as in a riveter, ham- 40 mer or drill, the movements of reciprocation of the sleeve are most conveniently effected by means of an electric motor contained in the casing of the tool. Inasmuch as direct current is very much to be preferred for 45 energizing the magnet, tools of this type have customarily been designed, so far as I am aware, for operation by direct current only. That is, they have been furnished with direct current motors for driving the 50 sleeve; the motor and coil for magnetizing the sleeve being sometimes in series and sometimes in parallel.

My present invention contemplates furnishing the tool with an alternating current 55 motor, or preferably with a universally wound motor, so that the same tool may be used with either direct current or alternating current, whichever is available, and in order to supply the electro-magnet with di-

rect current, my invention, in the preferred 55 embodiment, provides the tool with a direct current generator of low voltage, which is driven by the motor. A generator so driven may obviously be employed, if desired, in connection with a tool of this type furnished 60 with the ordinary direct current generator. Low voltage in the magnet circuit has the advantage of making the matter of insulation easier and, furthermore, permits the use of heavier wire, thereby cheapening the 65 construction.

A further object of the invention is to make an improvement in the reciprocating sleeve, whereby the expense of manufacturing the same is decreased and a better bearing surface is provided for the driven element, the armature core.

A further object is to provide certain novel means, to be hereinafter described, for preventing the armature from becoming dis- 75 placed with respect to or breaking away from the sleeve due to inertia.

The invention has for further objects such other new and improved constructions and devices relative to electrically operated per- 80 cussion tools as will be hereinafter described and claimed.

The invention is illustrated, in a preferred embodiment, in the accompanying drawings, 85 wherein—

Fig. 1 is a longitudinal sectional view of a drill constructed in accordance with my invention.

Fig. 2 is a view, in perspective, of the re- 90 ciprocating sleeve.

Fig. 3 is a sectional view taken on line 3—3 of Fig. 1.

Fig. 4 is a view, in perspective, of the armature shaft with the armatures for the 95 motor and generator thereon.

Fig. 5 is a sectional view on line 5—5 of Fig. 1.

Fig. 6 is a diagram illustrating the elec- 100 trical connections.

Fig. 7 is a sectional view, diagrammatic in certain particulars, illustrating a modified form of the invention in which a synchronous motor is employed, and

Figs. 8, 9 and 10 are longitudinal sectional views illustrating a certain preferred modi- 105 fication of the construction of the plunger and sleeve for preventing the latter from breaking away from or getting out of step

with the former; these three figures showing different relative positions of the parts of the same structure at different points in the stroke of the machine.

5 Like characters of reference designate like parts in the several figures of the drawings.

The operating parts of the device are enclosed in a casing consisting of a casting 10, a cylindrical member 11, a cap 12, closing the end of the cylindrical member, and a head 13 which is threaded into a cylindrical extension 14 on casting 10. The members 11 and 12 are secured to the main casting 10 by tie rods 15 threaded into lugs 16

15 on member 10 and engaged at their outer ends by nuts 17. Head 13 is formed with a boss 18 in which is a bushing 19 to receive the end of the tool shank 20. Attached to the casing is a handle piece and gear case

20 21 formed with a hand grip 22 which is hollow so as to make a place for the push button switch 23 by means of which the supply current to the operative mechanisms of the tool is controlled.

25 24 is an electro-magnet, the spool of which 25 is held between a boss 26 formed on the casing member 10 and a boss 27 on the head 13. In the magnet is a non-magnetic bearing 28 within which slides a sleeve 29 (Fig.

30 2), made of iron or steel with the middle portion 30 cut away so that it is relatively thin. The sleeve, therefore, consists of two pole pieces connected by a cylindrical body which contains such a small amount of metal that to all intents and purposes the pole pieces are magnetically insulated one from another.

Within the sleeve is a solid core 31 made of iron or steel and formed with a hardened 40 projection 32 adapted to strike the inner end of the tool shank 20.

The sleeve 29 is reciprocated by an electric motor, preferably a universally wound motor, capable of operation either by alternating or direct current. 33 indicates the field of the motor and 34 the armature, the latter being carried on a shaft 35 mounted in ball bearings 36 in the cap 12 and at the other end in ball bearings 37 arranged in a boss 38 formed in a web 39 on the central casing member 10. On one end of shaft 35 is a gear wheel 40 meshing with a gear wheel 41 on a countershaft 42 which turns in ball bearings 43 located in a boss 44 formed on the web 39. The sleeve 29 is connected by a connecting rod 45 with a wrist pin 46 on the gear wheel 41, the connecting rod being attached to lugs 47 on the upper end of the sleeve by means of a connecting pin 48. Preferably a ball bearing 49 is interposed 60 between the connecting rod and wrist pin.

The armature 50 of the generator is preferably carried on the armature shaft 35 of the motor. 51 indicates the field coils of 65 the generator and 52 the pole pieces, the gen-

erator being of the low voltage type. 53 designates the brushes for the motor commutator 54, and 55 the brushes for the generator commutator 56. The motor is shown as series wound, 57 (Fig. 6) indicating the 70 circuit and 58 the source of current supply. The field 51 of the generator is in shunt with the commutator of the generator; 59 (Fig. 6) indicating this circuit. The magnet 24 is supplied with direct current from the 75 generator through a circuit 60; the armature windings on shaft 35 are insulated by means of a disk 61.

In the construction shown in Figs. 1 and 2, the end of the sleeve 29 is closed and the 80 sleeve formed with exterior longitudinal slots 63 communicating with the interior of the sleeve through perforations 64. At the end of the out-stroke of sleeve 29 and core 31, the core is forced inwardly of the sleeve thereby 85 closing air ports 64. This produces an air cushion between the core and the inner end of the sleeve. The outer end of the sleeve is closed by an annulus 65, the opening in which is a trifle larger than the diameter 90 of the projection 32 on the core 31. On the back stroke the lag of the core tends to throw it out of its proper position in the sleeve. This is prevented by the cushion of air between the core and the annulus 65. 95

The operation of the device is as follows: The operator grasps the machine by hand grip 22. By pressing the push button of switch 23 the motor 33, 34 is set in operation revolving gear wheel 41, which causes reciprocation of sleeve 29. At the same time a low voltage direct current is generated by generator 50, 51, by means of which magnet 24 is energized. I have found that there is always residual magnetism in the pole pieces 100 of the generator field to start up the generator.

If such were not the case it would, of course, be possible to employ permanent magnets in the field of the generator. The reciprocation of sleeve 29 shifts or distorts 110 the magnetic field produced by magnet 24. This imparts reciprocating movement to the core 31. The relation between the core and the sleeve is, of course, an elastic one due to the magnetic attraction existing between 115 these elements. This magnetic spring is supplemented by the air cushioning arrangements between the core and the inner and outer ends of the sleeve. The primary object of having an air cushion at each end of 120 the core is to maintain the core in a central position in the sleeve so that the impacts of the core against the tool shank 20 will be uniform. In other words, the air cushion stiffens the magnetic spring. In small machines it would be feasible to omit the magnet 24 and rely entirely on the air cushions to center the plunger on the reciprocating sleeve. I prefer, however, to employ the magnet primarily for this purpose. 130

The expedient of turning down the center portion of the sleeve 29 so as to provide pole pieces substantially insulated magnetically from each other instead of forming the 5 sleeve with openings, as in the patent above referred to, has the advantage of economy of manufacture and also provides a perfectly smooth bearing of maximum area on the interior of the sleeve for the core 31.

10 In Fig. 7 I have illustrated a modified form of the invention according to which the machine is driven by a synchronous motor. The motor is in the nature of a synchronous converter having a commutator for the purpose of delivering direct current for exciting 15 the field of the solenoid 24^a.

The motor has a revolving armature, the windings thereof being connected in the usual manner, at one end to the collector 20 rings 68, 69, and at the other end to the commutator segments 67. The pole pieces 71 are provided with short circuited bars 72. The connections between the shaft of 25 the rotor and the reciprocating sleeve 29 are the same as in the machine previously described. The motor is started by current introduced into the windings of the armature through the commutator 67. 30 74 indicates the supply circuit in which is arranged a bi-polar double-throw switch 75. In one position of the switch (the one shown in Fig. 7) the supply leads 74 are connected with conductors 76, 77, which run to the brushes 78 of the commutator. When the motor is revolving in frequency with the supply circuit the switch 75 is reversed, cutting out the circuit 76, 77 and connecting with the supply leads conductors 79, 80 which lead to brushes 81, 82 35 bearing, respectively, on the slip rings 68, 69. The magnet 24^a is connected by wires 83, 84 with the commutator brushes. The current taken through this circuit is, therefore, transformed from alternating to direct current. 40 The field coil 73 on the motor is also shunted by means of wires 85, 86 from the commutator brushes. The short circuited bars aid the motor in starting. It is not so essential, when these bars are used, to bring 45 the motor to synchronous speed before throwing the switch 75.

In Figs. 8 to 10 inclusive I have shown a modification in the construction of the magnetizable sleeve for reciprocating the 55 cushion element or core, the purpose of which modification is to more effectually prevent the core from getting out of step or breaking away from the sleeve when the latter is run at a very high speed, for example. This 60 arrangement may be used either in place of the air cushion arrangement shown in Fig. 1 or as supplementing the same. It consists essentially of placing at opposite ends of the core or percussion element 31^b magnetizable 65 elements or disks 87, 88 which are movable

with the core within the reciprocating sleeve 29^b but are arrested in their movement as the core reaches the end of its stroke in each direction so that magnetic stresses are produced between such elements and the 70 ends of the core which counteract the inertia of the core. The disk 87 within the end of the sleeve to which the connecting rod is attached, is shown as formed with a central perforation through which passes a bolt 75 89 threaded into the end of the sleeve. The bolt has a head 90 against which the disk 87 is brought by a movement of the disk and core toward the outer end of the sleeve. The disk 88 is shown as formed with lugs 91 80 which project into guide slots 92 formed in the outer ends of the sleeve. The latter is preferably closed by a head 93 which fits the striking element 32^a on the core rather loosely. The movement of disk 88 inwardly 85 of the sleeve is limited to the length of the guide slots.

In Fig. 8 the parts are shown in the position which they will assume at the middle of the stroke, the in-stroke for example. 90 The magnetic attraction between the disks and the core hold the disks and the core together. When the sleeve reaches the end of the in-stroke (or possibly just before this) the force of inertia tends to throw the core 95 inwardly of the sleeve. If this movement is excessive so that by the time the out-stroke of the sleeve occurs, the core has not resumed its normal position, the effective operation of the machine is impaired. 100

But, as shown in Fig. 9, after the core has moved inwardly a certain distance, the inward movement of the disk 88 is arrested and any further relative movement of the core with respect to the sleeve is checked by 105 the magnetic stress between the disk and the end of the core. This stress very considerably augments the magnetic stress between the outer pole piece of the sleeve and the core. The latter, of course, does not become 110 effective until the outer end of the core passes, or at least reaches, the inner end of the pole piece. Unless this latter force is supplemented in some way there is a possibility that it will not be strong enough to 115 prevent the core, by its inertia, from breaking away from its central or balanced position in the sleeve.

Fig. 10 shows the parts in the position which they will assume (so far as I can determine it from theoretical considerations, observation being obviously impossible) at the end of the out-stroke or the beginning of the in-stroke. At this point the disk 87 comes against the head 90 of bolt 89 and any 125 further movement of the core outwardly, or assuming that the momentum of the core has been arrested by impact against the tool shank, any tendency of the sleeve to pull away from the core is checked by the mag- 130

netic stress set up between the disk 87 and the inner end of the core; this force being exerted directly against the end of the core so that it very materially supplements the 5 force of attraction exerted on the core by the inner pole piece of the sleeve. By providing the disks 87, 88 which lie flatwise on the ends of the core, the danger of the core getting out of place in the sleeve is checked.

10 Before this can happen the thrust on the core must overcome the magnetic attraction between the core and one disk or the other, the force of which is considerable.

While I have described my invention in 15 certain preferred embodiments, it will be understood that modifications might be made without departure from the spirit of the invention. Therefore I do not wish to be understood as limiting the invention except so far as the claims are specifically so limited.

I claim:

1. In apparatus of the character described, the combination of an electro-magnet 25 and armature therefor; means for producing a shifting of the magnetic field flux which carries the armature with it; and a generator driven by said means for energizing said magnet.

30 2. In apparatus of the character described, the combination of an electro-magnet and armature therefor; means comprising an electric motor for producing a shifting of the magnetic field flux which carries 35 the armature with it; and a generator driven by said motor for energizing said magnet.

3. In apparatus of the character described, the combination of an electro-magnet and armature therefor; means comprising 40 an electric motor for producing a reciprocatory shifting of the magnetic field flux which carries the armature with it; and a generator driven by said motor for energizing said magnet.

45 4. In apparatus of the character described the combination of an electro-magnet and armature therefor; means comprising an electric motor capable of operation by alternating currents for producing a reciprocatory shifting of the field flux of said electro-magnet which carries said armature with it; and a generator, the armature of which is on the same shaft with the armature of the motor, for supplying direct current to said 55 magnet.

5. In apparatus of the character described, the combination of an electro-magnet; a floating core armature in said magnet, a magnetizable sleeve interposed between the 60 magnet and core; a motor to reciprocate said sleeve, and a generator driven by the motor for supplying current to said electro-magnet.

6. In apparatus of the character described, 65 the combination of an electro-magnet; a

floating core armature in said magnet; a magnetizable sleeve interposed between the magnet and core; an electric motor for reciprocating said sleeve, and a generator, the armature of which is on the armature shaft 70 of the motor, for supplying current to said electro-magnet.

7. In apparatus of the character described, the combination of an electro-magnet; a sleeve of magnetizable metal arranged with- 75 in said magnet and formed so as to provide a pair of spaced pole pieces; a floating core in said sleeve; a series wound universal motor; a gear wheel on the armature shaft of said motor; a gear wheel meshed with the 80 first named gear wheel provided with a wrist pin; a connecting rod which connects the sleeve with said wrist pin; and a generator, the armature of which is carried on the armature shaft of the motor having a commutator, the brushes of which are in circuit with said electro-magnet, the field of the generator being in shunt with said commutator.

8. In apparatus of the character described, 85 the combination with an electro-magnet and armature; of an alternating current motor for producing a shifting of the field flux of the electro-magnet which carries the armature with it; and means operated by the motor for supplying direct current to said electro-magnet.

9. In apparatus of the character described, the combination with an electro-magnet and armature; of an alternating current motor 100 for producing a reciprocatory shifting of the field flux of the electro-magnet which carries the armature with it; and means operated by the motor for supplying direct current to said electro-magnet.

10. In apparatus of the character described, the combination of an electro-magnet, a floating core armature in said magnet, a magnetizable sleeve interposed between the magnet and the core; and a motor adapted 110 to be operated by alternating currents to reciprocate the sleeve provided with means for supplying a direct current to the coil of said electro-magnet.

11. In apparatus of the character described, the combination of an electro-magnet, an armature core therefor, a magnetizable sleeve interposed between the coil of the magnet and the core, means for reciprocating the sleeve, magnetizable disks at opposite ends of the core movable with the core within the sleeve, and means for arresting the movement of the disks as the core reaches the ends of its stroke in opposite directions so that magnetic tension is produced 115 between the disk and the core which resists the tendency of the core to get out of step with the sleeve.

12. In apparatus of the character described, the combination with an electro- 120

magnet having a floating core armature, means for producing shifting movements in opposite directions of the field of the magnet so as to reciprocate the core, magnetizable elements movable with the core and within the field of said magnet, and means for arresting the movements of said elements

as the core reaches the ends of its stroke in opposite directions for the purpose described.
